UNITED STATES PATENT OFFICE.

HENRY R. GILSON, OF BADEN, PENNSYLVANIA, ASSIGNOR TO NATIONAL METAL MOLDING COMPANY, OF PITTSBURGH, PENNSYLVANIA, A CORPORATION OF PENNSYLVANIA.

CABLE-ARMOR.

1,215,365.

Specification of Letters Patent. Patented Feb. 13, 1917.

Application filed October 2, 1914. Serial No. 864,613.

To all whom it may concern:

Be it known that I, HENRY R. GILSON, residing at Baden, in the county of Beaver and State of Pennsylvania, a citizen of the 5 United States, have invented or discovered certain new and useful Improvements in Cable-Armor, of which improvements the following is a specification.

My invention relates to such flexible cable 10 armor or conduit as is formed of two helically coiled superposed strips of metal arranged to interlock with each other and of such shape as to permit of a relative movement of superposed coils for the purpose of 15 bending the armor.

Of the several elements to be considered in such armor, it is desirable in the first place that it should possess a maximum degree of flexibility without being unduly 20 strained. However, the relative movement of the superposed coils, which is essential to the flexibility of the arms, must be so resisted as to prevent undue elongation of the armor when subjected to a longitudinal pull. 25 Also, it is desirable to have the armor strips of such configuration that the thickness of the armor, that is, the distance between the inner surface of the inside strip and the outer surface of the outside strip, shall be 30 reduced to a minimum, commensurate with its utility and efficiency in other respects.

With these considerations in view, it is the object of my invention to provide an armor of inner and outer strips having such specific 35 relative configuration as to afford a minimum outside diameter of the armor, and a maximum degree of flexibility thereof commensurate with the required limitations as to the permissible elongation when the 40 armor is subjected to the tension or pull test.

In the practice of my invention I provide an armor formed of two strips, one of which is curved throughout so as to be arcuate in cross section, and the other consisting solely 45 of a flat base or body portion with its opposite edges bent at less than a right angle thereto.

In the accompanying sheet of drawings I have illustrated my invention in two forms. 50 Figure 1 is an elevation of a short piece of armored cable, the armor being shown partly in section; Fig. 2 an enlarged cross sectional view of the two forms of strips shown in the same relative positions as the armor of Fig.

1; and Fig. 3 a view similar to Fig. 2, but 55 showing the armor strips arranged in reverse positions.

In the disclosure of Fig. 1 the curved or arcuate strip 1 forms the inner wall and the flat base strip 2, 3 the outer wall of the 60 armor which surrounds a cable 4. As will be readily seen, the outer strip has an extended flat base 2 and continuous edges 3 bent at less than a right angle to the base, while the inner strip 1 is continuously curved in the 65 form of an arc of a circle. When the armor is caused to bend, the edges 3 of the portions of the coils on the convex side of the bend slide upwardly upon the oppositely disposed and gradually increasing inclines of the 70 curved strip 1, thus affording a gradually increasing resistance as the radius of the bend diminishes, but permitting of an appreciable amount of flexure before such resistance becomes very great. Substantially the same degree of flexibility with increasing resistance thereto may be had by arranging the strips as indicated in Fig. 3, that is, the curved strip 1^a forming the outer wall and the flat base strip 2^a, 3^a the inner wall of the conduit. In 75 the armor of Figs. 1 and 2 a strip of paper 5 or other suitable material is shown between the edges 3 and the concave face of the strip 1, and in the armor of Fig. 3 a corresponding strip 5^a is shown. While either form of 80 armor may be advantageously used, that of Figs. 1 and 2 is the most desirable because the regularity or substantial continuity of its outer surface offers a minimum resistance when the armor is fished through small 85 openings.

The armor may be manufactured by any suitable means in the manner already indicated, namely, by helically coiling the inner strip with its edges turned outwardly, and the outer strip with its edges turned inwardly between the edges of the inner strip. The strips may be coiled directly upon the cable, or they may be formed into a tubular structure and the cable threaded through it. 90

It will be observed of the armor which I provide that, when subjected to a longitudinal pull, there will, because the upturned edges of the flat strip ride-up on the curved strip, be an immediate resistance throughout 95 its entire extent which will prevent the armor being stripped from, or slipped longitudinally upon, the cable. Furthermore, 100

when the cable is bent, the initial resistance will be slight, but will gradually increase as the radius of flexure is diminished. Also it will be observed that, for an armor having 5 these characteristics, and being otherwise of a practical construction, the thickness of the armor wall is reduced to a minimum.

I claim as my invention:

- 10 1. A cable armor formed of inner and outer metallic strips arranged in superposed interlocking helical coils, one of such strips having an extended flat base portion with its opposite immediately-adjoining sides bent at less than a right angle thereto to form a 15 continuous interlocking portion, and the other strip being arc-shaped in cross section, said bent sides of the first named strip resting in the concavity of the second named arc-shaped strip, and the convex side of the

arc-shaped strip forming one wall of the 20 armor.

2. A cable armor formed of inner and outer metallic strips arranged in superposed interlocking helical coils, the inner strip being arc-shaped in cross section with its 25 concave side facing outwardly, and the outer strip having an extended flat base portion with its opposite immediately-adjoining sides bent at less than a right angle thereto to form a 30 continuous interlocking portion, said sides resting in the concavity of the inner strip.

In testimony whereof I have hereunto set my hand.

HENRY R. GILSON.
